DESIGN FOR AN EYE SHIELD

Hazael E. Montgomery, Springfield, Ill.

Application November 18, 1940, Serial No. 96,658

Term of patent 3½ years

To all whom it may concern:

Be it known that I, Hazael E. Montgomery, a citizen of the United States and a resident of the city of Springfield, county of Sangamon, and State of Illinois, have invented a new, original, and ornamental Design for an Eye Shield, of which the following is the specification, reference being had to the accompanying drawing, forming a part thereof.

Fig. 1 is a perspective view of an eye shield showing my new design.

Fig. 2 is a front view of the same with parts broken away for convenience of illustration; and

Fig. 3 is an end view of the disclosure in Fig. 2.

My design for an eye shield is characterized by the specific configuration of the frame shield member and the eye brow members, all as shown.

I claim:

The ornamental design for an eye shield, as shown and described.

HAZAELE MONTGOMERY.
